UNITED STATES PATENT OFFICE.

DON V. TANTLINGER, OF LAWTON, OKLAHOMA.

TOY.

1,228,147.

Specification of Letters Patent. Patented May 29, 1917.

Application filed July 15, 1916. Serial No. 109,527.

To all whom it may concern:

Be it known that I, DON V. TANTLINGER, a citizen of the United States, and a resident of Lawton, in the county of Comanche and State of Oklahoma, have invented an Improvement in Toys, of which the following is a specification.

This invention is an improvement in toys and has particular reference to a device for hurling boomerangs.

An object of the invention is the provision of a mechanical device for hurling a boomerang which includes a movable member for receiving one end of the boomerang and pivoted to a stationary member, said movable member being adapted to be adjusted against the tension of a resilient element so that when released the boomerang will be hurled therefrom with great force.

Another object is to provide a device of this character which is simple in construction, easy to manufacture, and effective in carrying out the purpose for which it is designed.

The inventive idea involved is capable of receiving a variety of mechanical expressions, some of which, for the purpose of illustrating the invention, are shown in the accompanying drawing, in which—

Figure 1 is a perspective view of one embodiment of the invention.

Fig. 2 is a transverse sectional view thereof.

Fig. 3 is a side elevation of another form of the invention.

Fig. 4 is a perspective view of a still further form of the invention.

Fig. 5 is a similar view of another embodiment.

Fig. 6 is a section on the line 6—6 of Fig. 2.

What are now believed to be preferred forms of the invention are illustrated in the drawing and by referring to Figs. 1, 2 and 6 thereof it will be seen that the invention comprises a body portion 10 having extending transversely therethrough a shaft 11 having its ends extending beyond said body portion and provided on each end thereof with arms 12 and 13. On the end of the shaft which carries the arm 13 said shaft is provided with a bearing 14 having a notch 15 which receives a stop 16 secured to the body portion whereby the rotary movement of the shaft 11 is limited. Interiorly of the body portion the shaft 11 has coiled there-

about a spring 17 having one end secured to the body portion and the other end to the shaft so that when the arm 13 is rotated in one direction the tension of the spring about 60 the shaft will be increased and when said arm is released the same will be returned to its normal position, by said spring, with considerable force.

The arm 13 is provided, preferably on the 65 inner face thereof, with a socket member 18 for receiving one end of a boomerang 19 and it will thus be seen that when the arm 13 is drawn rearwardly against the tension of the spring 17 and then released, the boomerang 70 19 will be ejected from the socket member 18.

Referring to Fig. 3 the body 20 is preferably provided with a cut-out portion 21 in which is mounted one end of a leaf spring 75 22 the other end of which engages an arm 23 provided with a socket for receiving a boomerang or other projectile. By drawing the arm 23 rearwardly against the tension of the spring 22 and then releasing the same 80 said arm is returned to normal position, being limited in its return movement by the shoulder 24, and the projectile hurled therefrom.

In Fig. 4 there is shown another form of 85 the invention in which the body portion or relatively stationary member 25 is provided with an opening 26 for receiving the thumb of the left hand of the operator and said body portion is preferably of rectangular 90 formation. To the rear edge of the body portion 25 the same has pivoted at 27, an arm 28 provided at its bottom with a cut-out portion 29 which permits of said arm being drawn rearwardly and away from the body portion. The upper end of the arm 28 is provided with a socket 30 for receiving one end of a boomerang and embracing the body portion 25 and the arm 28 adjacent the upper ends thereof are a number of elastic 95 bands 31 against the tension of which the arm 28 is drawn rearwardly. The arm 28 is provided on each side thereof with a grip 32 which is grasped when stretching the bands 31 and when said grips are released 100 the bands return the arm, with considerable force, to its normal position thus ejecting the boomerang from the socket 30.

The form of the invention illustrated in Fig. 5 preferably includes a body portion 33 110 preferably shaped similarly to the handle of a pistol and has pivoted therein an arm 34

provided with a socket 35 for receiving one end of a boomerang. A leaf spring 36 has one end secured to the butt of the body portion and the other end engages said arm 34 so that when drawn rearwardly and then released by means of a trigger 37, said spring will cause the arm 34 to return to its normal position and eject the boomerang therefrom, the return of said arm to normal position being limited by means of a pin 38.

What is claimed is:

1. A toy of the character described, comprising a body portion, a rotatable shaft mounted in the body and having one end 15 projecting through the same, a spring coiled on the shaft within the body for actuating it, an upwardly projecting arm secured to the projecting end of the said shaft and having on one face adjacent the outer end 20 thereof a socket open at the top and adapted to receive a projectile, said arm being adapted to operate the shaft to put the spring under tension and when released to hurl the projectile, and coöperating means 25 on the shaft and body for limiting the movement of the shaft in one direction.

2. A toy of the character described, comprising a hollow body portion, a rotatable transverse shaft mounted in the body with its ends projecting beyond the body, an arm 30 on each projecting end of the shaft, one of the arms projecting upwardly and provided on one face adjacent its outer end with a socket open at the top, a spring coiled upon the shaft and having one end secured to the 35 shaft and the other to the body, and co-operating means on the shaft and body for limiting the movement of said shaft in one direction.

3. A toy of the character described, comprising a hollow body, a spring actuated shaft mounted in the body and having one end projecting beyond the body, an arm on the projecting end of the shaft and provided with a socket, a notched bearing on the projecting end of the said shaft and a stop on the body and engaging the notch of the said bearing.

DON V. TANTLINGER.
